CLAIM

The ornamental design for an actuator for push-pull cables or electric switches for bicycles, as shown.

DESCRIPTION

FIG. 1 is an end elevational view of an actuator for a push-pull cable or electric switch for bicycles showing my new design;

FIG. 2 is a side elevational view thereof;

FIG. 3 is a side elevational view thereof, from the opposite side of FIG. 2;

FIG. 4 is a perspective view showing the top and a side and end thereof;

FIG. 5 is an end elevational view thereof, from the end opposed to FIG. 1;

FIG. 6 is a top plan view thereof; and

FIG. 7 is a bottom plan view thereof.

FIG. 1

FIG. 2

FIG. 3

FIG. 4

FIG. 5

FIG. 6

FIG. 7
